UNITED STATES PATENT OFFICE.

WILLARD A. WHEELER, OF ATKINSON, NEBRASKA.

CONCRETE-MIXER.

1,049,018.

Specification of Letters Patent. Patented Dec. 31, 1912.

Application filed January 20, 1912. Serial No. 672,348.

To all whom it may concern:

Be it known that I, WILLARD A. WHEELER, a citizen of the United States, residing at Atkinson, in the county of Holt 5 and State of Nebraska, have invented new and useful Improvements in Concrete-Mixers, of which the following is a specification.

This invention relates to an apparatus 10 for mixing concrete and other materials, the primary object of the invention being to provide a frusto-conical rotary mixing drum which is adjustable to regulate its feeding and mixing actions and which embodies a novel construction of feeding and 15 mixing devices, whereby efficiency of operation is obtained.

A further object of the invention is to provide novel means for mounting the 20 drum; whereby an easy and free revoluble motion thereof is insured; novel means for driving the drum and feeding the material thereto; novel means for adjusting the drum to vary its angle of inclination; and 25 means for moistening the material so that it may be delivered in proper condition for handling.

The invention consists of the features of construction, combination and arrangement of parts, hereinafter fully described 30 and claimed, reference being had to the accompanying drawings, in which:—

Figure 1 is a sectional plan view of the mixer taken on the plane indicated by the 35 line 1—1 of Fig. 2. Fig. 2 is a central vertical longitudinal section of the same. Fig. 3 is a cross section on line 3—3 of Fig. 2. Fig. 4 is a detail section on line 4—4 of Fig. 3. Fig. 5 is a detail section 40 on line 5—5 of Fig. 3. Fig. 6 is a cross section through the inlet end of the drum. Fig. 7 is a cross section on line 7—7 of Fig. 2 through the center of the drum. Fig. 8 is a fragmentary plan view of the 45 interior of the drum as it would appear if spread out in a flat condition.

Referring to the drawings, 1 designates a suitable supporting frame provided at one end with a superposed hopper 2 for 50 the reception of the material to be delivered to the mixing drum. The opened end of

mouth 3 of this hopper is disposed above the upper stretch of a longitudinally extending, horizontal feed belt 4 mounted upon rolls 5 and 6, which upper stretch of the 55 belt receives the material from the hopper and is movable in a forward direction to convey such material to the inlet end of the drum. Journalized in suitable bearings on the frame is a transversely extending drive 60 shaft 7 provided at one end with a pulley 8, whereby it may be driven from any suitable source of power. This shaft carries a pulley 9 connected by a drive belt 10 with a pulley 11 on the shaft of the roll 5, where- 65 by the feed belt is driven.

The forward end of the feeder 5 projects into the inner, reduced inlet end of the mixing drum 12, which drum is of frusto-conical form and arranged horizontally or 70 inclined at a slight angle downwardly and forwardly between its reduced inlet end and its outer or enlarged delivery end for the feed of the material therethrough by gravity, which is effected in the rotation of 75 the drum by the inclination of the bottom portion of the drum due to its frusto-conical form. The drum extends through suitable supporting portions 13 and 14, which inclose the same, and which are re- 80 spectively provided with spaced pairs of bars or plates 15 and 16 which carry sets of pivot pins or bolts 17 and 18 on which are revolvably mounted supporting wheels or rollers 19 and 20. These wheels or rollers 85 are annularly grooved to engage the vertical flanges and horizontal webs of T-shaped track rails 21 and 22 secured to and encircling the drum, whereby the drum is supported to have a free and easy revoluble 90 motion.

The supporting portion 14 of the drum at or near its larger end is in the form of a vertically adjustable auxiliary frame provided at its sides with lugs 23 having threaded openings for the passage of vertical shafts 24 and nuts to engage threaded portions 25 of said shafts, which latter are mounted in suitable bearings 26 on the main frame 1. The shafts 25 carry at their lower ends 100 gears 27 which mesh with worms 28 on a transverse adjusting shaft 29 mounted

on the frame 1, said shaft being provided at one end with a fixed head 30 having an annular series of sockets to receive a suitable lever or turning tool 31, whereby the 5 shaft may be turned in one direction or the other to rotate the shafts 24 and thereby raise or lower the drum to vary its degree of inclination to retard or accelerate its feed motion as occasion may require. As 10 the drum tilts mainly on its reduced end as an axis or point of fulcrum, the wheels or rollers 19 are fitted to slide on their axle bolts 17, to permit and compensate for such tilting motion.

15 Supported upon the frame 1 is a water feed pipe 32 connected at its inlet end with a hose 33 leading from a suitable source of water supply. This pipe is provided with a controlling valve 34, and at its delivery end 20 is formed or provided with an elbow 35 arranged in advance of the delivery end of the drum and terminating in a spray pipe or extension 36 extending into such end of the drum, whereby the concrete or 25 material undergoing the mixing process may be moistened to any desired degree prior to discharge. The drum carries between its two points of support a sprocket ring 37 connected by a drive chain 38 with 30 a sprocket wheel 39 on the forward end of a longitudinally extending shaft 40, the rear end of which carries a beveled gear 41 meshing with and receiving motion from a similar gear 42 on the drive shaft 7.

35 Arranged upon the interior of the drum are annular series of longitudinally extending right angular mixing paddles or blades 43, arranged in staggered relation or with the paddles or blades of the several annular 40 rows or series arranged successively in line between the paddles or blades of the adjacent rows or series. These paddles or blades operate in the forward feed of the material to take up and elevate the same and 45 to turn over the particles of the material to effect a thorough agitation and admixture thereof. The front series of blades 43 terminate a suitable distance from the delivery end of the drum, while the rear series of 50 blades terminate a suitable distance from the inlet end of the drum, leaving at the latter-named end a receiving space 44 in which are arranged two or more series of agitating and feed paddles or blades 45, 55 arranged in staggered relation to each other. The delivery end of the belt projects into the said space 44 to deposit the material therein, and the blades or paddles 45 are disposed obliquely or spirally to the axis of 60 the drum to spread out and distribute the material around the surface of the drum and feed said material longitudinally toward the center of the drum, where it is agitated and admixed by the paddles or

blades 43, insuring a rapid feeding of the material, as well as a thorough combination of the particles thereof. The material finally discharges at the widened delivery end of the drum after being moistened to a desired degree either upon the floor or 70 ground or into suitable receptacles. The inlet end of the drum is provided with an inwardly projecting annular flange 46, whereby it is contracted and a stop or barrier furnished to prevent escape of the material at such end of the drum. When the drum is tilted forwardly to retard the feed of the material, this flange also acts to prevent the material from escape before it is initially gathered up and fed forward by 80 the blades or paddles 45.

From the foregoing description, taken in connection with the drawings, the construction and mode of operation of my improved mixing apparatus will be readily understood and it will be seen that the invention provides a device of this character which is simple of construction, adapted to be built and operated at a comparatively low cost, and which insures a thorough agitation and 85 admixture of the material under treatment. It will, of course, be understood that while the device is especially adapted for mixing concrete and the like, it may be also employed for mixing other materials. 90

Having thus described the invention, what I claim as new is:

1. In a mixing apparatus, the combination of a main frame, inner and outer auxiliary frame portions rigidly and adjustably 100 mounted respectively upon the main frame, a frusto-conical drum extending through said auxiliary frame portions and provided with annular tracks in line therewith, grooved rollers upon the auxiliary frame 105 portions and engaging said tracks, the rollers of the inner auxiliary frame portion being loosely mounted to permit the drum to tilt vertically, nuts upon the adjustable auxiliary frame portion, screw shafts upon the main frame and engaging said nuts, a transverse power shaft journaled upon the frame, and worm gearing between the same and the respective screw shafts. 110
2. A mixing apparatus comprising a 115 main frame, fixed and vertically adjustable auxiliary frames thereon carrying sets of grooved rollers, the grooved rollers upon the fixed auxiliary frame being free for sliding motion on their axes, a frusto-conical drum projecting through the auxiliary frames and provided with annular track rails engaging said rollers, said drum being adjustable with the adjustable auxiliary frame and tilttable on the rollers of the fixed 120 auxiliary frame and provided with internal feeding and mixing blades, a water supply pipe projecting into the enlarged end of the 125

drum, and supported by and movable with the adjustable auxiliary frame, means for feeding the material into the reduced end of the drum, means for revolving said drum, and means for adjusting the adjustable auxiliary frame to tilt the drum in a vertical plane.

In testimony whereof I affix my signature in presence of two witnesses.

WILLARD A. WHEELER.
